HOOK BELL FOR A GARMENT BAG CARRIER

James G. Peters, 1 Penrose Lane,
Colorado Springs, Colo. 80906

Filed Aug. 16, 1972, Ser. No. 281,179

Term of patent 14 years

Int. Cl. D8—99

U.S. Cl. D8—154

FIG.1

FIG. 2

FIG. 1 is a bottom perspective view of a hook bell for a garment bag carrier showing my new design;

FIG. 2 is a side perspective view; and

FIG. 3 is a bottom plan view.

I claim:

The ornamental design of a hook bell for a garment bag carrier, substantially as shown.
